UNITED STATES PATENT OFFICE.

WILLIAM H. BROADHEAD, OF CLEVELAND, OHIO, ASSIGNOR OF TWO-THIRDS,
BY DIRECT AND MESNE ASSIGNMENTS, TO JACOB BOESEL, OF SAME
PLACE.

DOOR-CHECK.

SPECIFICATION forming part of Letters Patent No. 445,462, dated January 27, 1891.

Application filed May 24, 1890. Serial No. 352,999. (No model.)

To all whom it may concern:

Be it known that I, WILLIAM H. BROADHEAD, a citizen of Canada, residing at Cleveland, in the county of Cuyahoga and State of Ohio, have invented certain new and useful Improvements in Door-Stops; and I do hereby declare that the following is a full, clear, and exact description of the invention, which will enable others skilled in the art to which it appertains to make and use the same.

My invention relates to door-stops, and belongs to that class of stops which are designed to be attached to the bottom of the door and to press upon the floor when in working position, so as to hold the door open, or partially open, as may be required.

To this end the invention consists in a bracket adapted to be attached to the door, a sliding bolt, and an eccentric, with a lever to operate the bolt, all constructed substantially as shown and described, and particularly pointed out in the claims.

In the accompanying drawings, Figure 1 is a perspective view of the outside corner of a door with one of my improved stops attached thereto and in working position. Fig. 2 is a detail in perspective of the bracket, which is fixed to the door. Fig. 3 is a perspective of the sliding bolt. Fig. 4 is a side elevation of the cam with the eccentric, showing the inside thereof. Fig. 5 is a rear elevation of the bolt, and Fig. 6 is a cross-section thereof on line $x-x$, Fig. 5.

A represents a section of a door, and B a bracket secured to the door to one side or the other, as may be found most convenient, and in such relation to the floor that the stop will be in good working position. This bracket has a pair of ears, through which it is screwed firmly to the door, and projecting some distance from its face is a head C, provided with parallel sides and arranged to stand vertically, so as to form a suitable support and guide for the bolt D. The head C is formed preferably with its sides converging slightly toward the front face, on which is the pivot-pin or spindle c, adapted to serve as a support for the eccentric. At the base of the spindle c is a collar c', having about

the depth of the thickness of the bolt D, the 50 sides of the collar being flattened to correspond with the flat sides of the head C.

The bolt D has rearwardly-flaring flanges or sides d, adapted to the construction of the head C, and designed to ride and slide freely 55 thereon, the said head forming a guide, as well as a support, for the bolt, and the side flanges of the bolt serving to keep the bolt in proper working relation upon the head. On the face of the bolt, over its top, is a vertical 60 slot d', the edges of which are adapted to fit at the side of the collar c', and immediately below this slide, midway of the length of the bolt, on the face thereof, is a lug or projection d² at one side of the longitudinal center 65 of the bolt, and below said lug is an overhanging lip or projection d³, which serves to engage the outer edge of the eccentric, substantially as shown in Fig. 1, to assist in keeping said eccentric in working position in 70 connection with the lug d².

E represents the eccentric, which has a hole e at one side of its center adapted to fit upon the spindle c, on which it is secured by slightly riveting or flattening the end of the said spindle to form a sufficient head to keep the eccentric in working position. On the inside of the part E is a groove e', along the inner edge of which are a series of scallops e², and a handle e³ serves to operate the said part. 80

It will be seen that the entire device as thus constructed consists of three parts—the bracket B, the bolt D, and the eccentric E. In putting the parts together the bolt B is first placed in position upon the head C, with 85 the spindle projecting through the slot in the bolt. The eccentric is then placed on the spindle with the lug d² entering the eccentric groove and the lip d³ overhanging the outer edge of the eccentric. Then when the end of 90 the spindle is slightly upset, so as to keep the eccentric in position, and the parts thus united are attached to the door in proper working relation with respect to the floor the door can be stopped at any desired point by simply 95 turning the eccentric far enough to project the foot d⁴ down upon the floor. As shown in Fig. 1, the bolt B is raised to its highest ele-

vation, and when in this position the spindle c and the lug d^2 necessarily are brought very near together. Then by the use of the toe of the shoe the eccentric can be carried around 5 to the left a greater or less distance, as may be required, to lock the door, and as a forward pressure occurs and the lug d^2 bears against the scalloped edge e^2 of the eccentric the said scallops serve to lock the eccentric 10 and bolt at whatever point they may be left. If a further turn be made after such locking begins, a distinct accent occurs as each successive scallop is reached, and thus not only the door is locked in position against swinging, but the mechanism is interlocked in such 15 manner that it will stay in that position until released.

Having thus described my invention, what I claim as new, and desire to secure by Letters Patent, is—

1. The bracket having a head with parallel sides and a spindle projecting centrally from the face of the head, a bolt having a longitudinal slot with sides adapted to the sides

of said head and a lug on its face at one side 25 of its center and near the inner end of said slot, and an eccentric having a groove engaging the lug on the bolt, substantially as described.

2. The bracket provided with a head and 30 spindle, and a slotted bolt supported on the said head and having a lug on its face, in combination with a scalloped eccentric engaging said lug, substantially as described.

3. In a door-stop, the bracket having a head 35 with parallel converging sides, and a slotted bolt having its sides flared to match the said head and provided with a lug d^2 at one side of its center, in combination with the eccentric having a scalloped edge e^2 to engage said 40 lug d^2 , and a handle, substantially as described.

Witness my hand to the foregoing specification this 10th day of May, 1890.

WILLIAM H. BROADHEAD.
